(57) **CLAIM**

The ornamental design for a vacuum sealing appliance, as shown and described.

DESCRIPTION

1. Vacuum sealing appliance

1.1 : Front and top perspective view

1.2 : Back and top perspective view

1.3 : Front and bottom perspective view

1.4 : Front

1.5 : Back

1.6 : Right

1.7 : Top

1.8 : Left

1.9 : Bottom

The broken lines in the drawings show unclaimed environment only and form no part of the claimed design; the thin lines in the drawings illustrate the shapes of the three-dimensional surface.
